Des. 178,843
Patented Sept. 25, 1956

178,843

AUTOMATIC INERT ARC WELDING MACHINE

Louis C. McNutt, Scotch Plains, N. J.

Application January 6, 1955, Serial No. 33,863

Term of patent 14 years

(Cl. D26—1)

FIG. 1

Figure 1 is a side perspective view of an automatic inert arc welding machine showing my new design; and

Figure 2 is a perspective view taken from the opposite side thereof.

I claim:

The ornamental design for an automatic inert arc welding machine, as shown.
